UNITED STATES PATENT OFFICE.

FREDERICK OLSEN, OF WASHINGTON, DISTRICT OF COLUMBIA.

EXPLOSIVE COMPOSITION.

1,376,029.

Specification of Letters Patent. Patented Apr. 26, 1921.

No Drawing.

Application filed May 22, 1920. Serial No. 383,592.

To all whom it may concern:

Be it known that I, FREDERICK OLSEN, a subject of the King of Great Britain, and a resident of Washington, in the District of Columbia, have invented an Improvement in Explosive Compositions, of which the following is a specification.

The object of my invention is the production of a non-freezing explosive composition, which will be useful either in underground places, such as mines or tunnels, or in open places, such as quarries or excavations, or in any other places in which explosives may be used.

My composition consists of a mixture of a propellant powder, such as is found in the forms known as nitrocellulose smokeless powder, or cordite, with either ammonium perchlorate or with nitro-hydrocarbons such as 15 tri-nitro-toluene, or both, and with or without the ordinary so-called "dope" ingredients of dynamites or blasting powders, such as combustible non-explosive carbonaceous materials (e. g. wood meal, flour), inorganic 20 nitrates (e. g. saltpeter), manganese dioxide, the purpose of which is to fix any free chlorine and also act as an oxidizing agent, 25 flame reducers (e. g. sodium chloride), temperature increasing materials (e. g. ferrosilicon, calcium silicide).

It is well known that nitrocellulose has long been used in the manufacture of explosives, and attempts have been made to use nitrocellulose with nitroglycerin and the ordinary ingredients of dynamites and blasting 35 powders as enumerated above, but the lack of success, which usually attends the use of these products has resulted from their insensitiveness. It has been my experience that when 40 the nitrocellulose is used in amounts more than say 5 per cent of the weight of the nitroglycerin, or other liquid nitric acid ester of aliphatic alcohols, mixtures are obtained, which have a very slight ability to propagate 45 the wave of detonation, especially after the mixture has been stored for a few months. If, instead of nitrocellulose, smokeless powder or cordite be substituted as an ingredient, the resultant mixture would be equally insensitve and inefficient.

I have discovered that, if, instead of nitroglycerin, ammonium perchlorate, or nitro-hydrocarbons such as tri-nitro-toluene are used

as the explosive base, explosive mixtures having very desirable properties are obtained.

The essential feature of the explosive composition herein described is that it affords an outlet for surplus or waste, propellant powders, the utilization or disposal of which presents a formidable problem.

For example, not only does the use of ammonium perchlorate assure a complete detonation of the nitrocellulose with the use of an ordinary number six detonator, and an excellent propagation of the explosive wave, but also serves as an oxygen carrier for the nitrocellulose, thereby procuring a greater strength and freedom from obnoxious fumes.

Many grades of powders can be obtained by varying the proportions of the ammonium perchlorate and nitrocellulose. For example, grades can readily be made to correspond to the twenty, thirty, forty per cent., etc., nitroglycerin dynamites or ammonium nitrate powders.

The following mixtures may serve as examples of powders which can be made:

	Per cents.					
Ammonium perchlorate.....	55	to	25			
Tri-nitro-toluene.....	85	to	25			
Nitro-cellulose.....	15	to	75	15	to	75
or—						
Ammonium perchlorate.....	30	40	40	20	20	20
Tri-nitro-toluene.....	30	30	30	20	20	20
Nitro-cellulose.....	40	15	30	30	30	30
Wood meal.....	5	10	10	3	5	5
Paraffin wax.....	20	10	20	17	10	10
Ground vegetable ivory.....	10	10	10	5	5	5
Niter.....			30	20	20	20
Manganese dioxide.....			30	20	20	20
Perchloric acid.....				25	25	25
Sodium chloride.....					10	10
						90

A greater cohesiveness may be secured by the use of mixtures of tri-nitro-toluene and dinitro-toluene, liquid tri-nitro-toluene, various liquid or semi-liquid nitro-hydrocarbons, or other common binding agents, such as castor oil, shellac compounds, etc. The use of these substances does not, however, vary the nature of my invention, and I claim my invention with or without their use.

The most suitable results are obtained when the smokeless powder or cordite is ground so that 100% will pass through a standard twenty mesh sieve, and at least 50% will pass through a fifty mesh sieve. But I do not wish to limit my invention

by the suggested use of this granulated form, or by the suggested pulverization which I have indicated. My invention covers the use of the said material with or without this pulverization.

It may be found desirable to use some other perchlorate than ammonium perchlorate, as for example, potassium perchlorate. My invention covers the use of any available inorganic perchlorate.

Having described my invention, what I claim as new and desire to secure by Letters Patent, is:

1. The herein described composition of matter, containing an inorganic perchlorate,

a nitro-hydrocarbon, a propellant powder, a combustible non-explosive material, chlorin fixing material and a flame temperature regulating material.

2. The herein described composition of matter, containing an inorganic perchlorate, a propellant powder, a combustible non-explosive material, a chlorin fixing material and a flame temperature regulating material.

25

3. The herein described composition of matter containing an inorganic perchlorate, a propellant powder, a combustible non-explosive material and chlorin fixing material.

FREDRICH OLSEN.
